UNITED STATES PATENT OFFICE.

CLYDE S. WHIPPLE, OF NEWARK, OHIO, ASSIGNOR TO A. H. HEISEY & CO., OF NEWARK, OHIO.

DESIGN FOR A TUMBLER OR SIMILAR ARTICLE.

46,646.

Specification for Design.

Patented Nov. 10, 1914.

Application filed April 6, 1914. Serial No. 830,062. Term of patent 7 years.

To all whom it may concern:

Be it known that I, CLYDE S. WHIPPLE, a citizen of the United States, residing at Newark, Ohio, have invented a new, original, and ornamental Design for a Tumbler or Similar Article, of which the following is a specification, reference being had to the accompanying drawing, forming part thereof.

Figure 1 is a side elevation of a tumbler illustrating my design. Fig. 2 is a bottom plan view.

The tumbler has a series of uniformly large plane-faced panels extending around the tumbler from the bottom to about $\frac{2}{3}$ of the length thereof. The characteristic fea-

ture of these panels is their straight horizontal upper ends joined to one another by short bats-wing curves whereby the tops of the panels are brought into substantially parallelism with the upper edge of the tumbler and the bottom thereof, when seen in side view.

I claim:

The ornamental design for a tumbler or similar article, substantially as shown and described.

CLYDE S. WHIPPLE.

Witnesses:

GEO. A. SMELTZ,
GEO. E. GRAETEO.
